DIFFERENTIAL ROLL CRUSHER

Stanley D. Hartshorn, Wayne, Pa.

Application June 30, 1938, Serial No. 216,666

6 Claims. (Cl. 83—45)

This invention relates to improvements in grinding mills of the roller type in which material is crushed against a grinding surface by freely rotatable rollers which travel along the surface, comminuting the material by direct pressure and rotated by their engagement with the material. Such mills are frequently constructed with a plurality of rollers traveling along an annular grinding surface which may be either horizontal or vertical.

A feature of the invention is the improvement of the comminuting action of the rollers by producing a differential or sliding movement between the crushing surface of a roller and the contiguous portion of the grinding surface. This is preferably accomplished by retarding or braking the rotation of each roller, and a specific feature of the invention is the utilization for this purpose of a magnetic brake, thereby avoiding friction, eliminating material resistance to roll rotation at low speed, and permitting convenient regulation of the braking effect. A generator type brake may be employed, and the current generated by the braking action may be utilized, for instance, to dry the material fed through a suitable electric heater.

The invention also includes the use of drive means such as an electric motor for accelerating the rotation of the roller and thereby producing the differential movement between the roller and the grinding surface. A specific feature includes the association with the roller of a motor-generator type unit which may be used either as a motor or as a magnetic brake to produce the indicated differential movement.

A further purpose is to provide a roller mill with an annular grinding ring, which preferably has an inner face sloping upwardly and outwardly to a sufficient extent to discharge ground material by centrifugal force over the upper edge of the ring and bowl. The lower face of bowl 16

In mills of this type, which are generally used to make a very fine product, difficulty has been encountered in the use of screens for removing the over-size because of the tendency of fine

screens to become blinded. A further object of the invention is to provide a screening arrangement which will pass a relatively fine product with a substantially diminished tendency to be

obstructed during use. This is accomplished by employing a screen having openings substantially larger than the desired size of the screened product, and projecting the ground material against the screen at a substantial angle and with sufficient velocity so that particles

because of such angle and velocity, while the tendency of the screen to blind will be greatly reduced due to the decreased tendency of particles approximating the mesh size to become lodged in the meshes. For this purpose the screen is arranged around the discharge zone in such manner that there is rapid rotary movement between the discharge and the screen, which may be accomplished either by rotating the screen relative to a stationary grinding surface, by rotating the grinding surface relative to the stationary screen, or by combining these features.

Other objects and advantages will appear from the following description considered in connection with the accompanying drawings, in which:

Fig. 1 is a vertical central section through a roller mill provided with a rotating bowl; Fig. 2 is a horizontal section on line 2—2 of Fig. 1 with parts broken away; Fig. 3 is a diagram of the magnetic brakes, feed heater and connections; Fig. 4 is a view similar to Fig. 1 showing a roller mill of the air discharge type with a stationary grinding surface; Fig. 5 is a fragmentary side elevation of a roller housing showing a mechanical brake; Fig. 6 is a plan view of the mechanical brake structure.

In the construction shown in Figs. 1—3, the mill is mounted on a base 10, carrying a motor 11 directly connected to a shaft 12 journaled in thrust bearings 13 in the bottom 14 of housing 15. Shaft 12 carries grinding bowl 16, carrying

scraper or impellers 18 traveling along the bottom 14 arranged to sweep ground material to a discharge outlet 20.

A plurality of grinding rollers 21 is mounted in rolling relation to ring 17, each roller 21 being fixed on a shaft 22 journaled in a shaft casing 23 pivoted at 24 to the top 25 of housing 15 for movement toward and from the ring 17, and provided with an arm 26 biased upwardly against

stop 27 on bracket 28 by a spring 29 carried by said bracket which is mounted on the body 15.

An suitable braking arrangement engaging each shaft 22 is provided, preferably at the upper end of the shaft above casing 23. The brake may be of the magnetic type, including a rotor

50

55

50

30 fixed to the upper end of shaft 22 and stator elements 31 mounted in a suitable frame 32 on the upper end of casing 23. The units 31 are suitably connected by leads 33 to an electric 5 heating unit 34 surrounding the feed inlet passage 35 discharging through the top 25 of the housing into bowl 16.

An annular screen 36 mounted beneath top 25 and having a lower margin immediately adjacent the upper edge of bowl 16 is arranged to receive material discharged centrifugally across the upper edge of ring surface 18 during operation.

A suitable fan arrangement may be provided 15 for assisting the removal of the screened product, and in the form illustrated includes fan vanes 37 mounted on the outer face of bowl 16 between the bowl and the housing 15, and preferably having a suitable helical inclination to provide a 20 substantial downward current of air. The blades 19 below the bowl will cooperate in discharging air from the bowl especially when employed in conjunction with a tangentially arranged outlet 20 as illustrated.

25 In the arrangement shown in Fig. 4 the basic mode of operation is similar but the bowl is stationary while the rollers are rotated as a unit. In this construction the bowl 40 is mounted through lugs 41 on the housing 42, and the 30 shaft casings 23 are pivoted at 43 on forks 44 carried by head 45 fixed to shaft 46 driven through bevel gears 47 by drive shaft 48. The usual ploughs 45a mounted on a downward extension of head 45 are employed to raise the 35 material from the bottom of bowl 40 into the path of rollers 21.

The mill is of a well-known air discharge type, and the showing is therefore somewhat diagrammatic, as the inventive feature may be incorporated 40 in known mills of this type having various features and details omitted in the present disclosure. In the illustrated arrangement the air enters through passage 20, travels through the grinding zone to pick up the pulverulent material 45 in any desired manner, as by passing around the periphery of bowl 40, and thence upwardly and out of casing 42 through outlet 42a. The air is propelled in any desired manner, as by the usual fan (not shown).

50 In this arrangement the magnetic brake units 31 are mounted in housings 49 on the shaft casings 23 and are connected through flexible leads 50 with slip rings 51 on shaft 46, the rings being connected through brushes 53 with the leads 33 55 connected to the heating coil 34. Brushes 53 may be carried by bracket 52 mounted on housing 42.

The feed passage 56 carrying heater 34 extends through the side of casing 42 in position to discharge the feed into bowl 40. In this arrangement the screen 36 has not been shown, but such omission is not restrictive, since the principles of screen arrangement and operation set forth herein are obviously applicable to this type of 65 mill.

While brakes of the magnetic type have certain advantages, the rotation of the roller shafts may be retarded in other ways. A mechanical brake of the centrifugal type suitable for this 70 purpose is illustrated in Figs. 5 and 6. It includes a frame disc 58 fixed to shaft 22 and suitable supporting radial arms 59 biased toward the center by spring 60 extending around pins 61 on arms 59. Said arms are radially slidable in 75 guideways 62 at the outer edge of disc 58 and

carry shoes 63 engageable with the inner face of brake drum 64 mounted on the upper end of shaft casing 23.

The differential movement between the rollers and the grinding surface may also be produced 5 by driving each roller at a rate of rotation greater than that resulting from rolling contact with the material. This may be conveniently accomplished by an electric motor connected to the roller shaft. Since the magnetic brakes here- 10 tofore described are of the motor-generator type, they can be employed as motors, it being of course understood that they are suitably wound and connected in well known manner for this purpose. Moreover, the same unit may be used 15 alternatively as a motor or as a magnetic brake, as by connecting leads 33 to a source of power G.

The electrical arrangement is of course dia- 20 grammatic and omits features and characteristics known to electrical engineers as necessary or desirable but which are unnecessary to an understanding of this invention. However, since the electrical characteristics of the heating unit 34 when the units 31 are employed as brakes should be substantially different from their characteristics when said units are driven as motors, a separate heating unit 34a is disclosed. Switch 55 is suitably connected to units 34, 34a, generator G and magnetic units 41 as shown in Figure 3 so that when units 31 are operated as 30 magnetic brakes, the generator current will pass through heating unit 34, and when they are connected to generator G and operate as motors the current from the generator will pass through heating unit 34a. 35

The method of operation will be in general apparent to those familiar with mills of the illustrated type. In the arrangement shown in Fig. 1 the material discharged through passage 35 into bowl 16 is ground against bowl ring 17 by rollers 40 21, being forced upwardly along face 18 of the ring by centrifugal force and being discharged in a substantially tangential direction by centrifugal force into contact with screen 36. The over-size will fall back into bowl 16 for regrinding while the fines, assisted by the fan vanes 37 and blades 19 will pass downwardly between bowl 16 and the housing 15 and out through passage 20. When bowl 16 is rotated at full speed rollers 21 will tend to rotate at the same peripheral speed as face 18; but will be retarded by the action of the magnetic brake units 31 on rotor 30, which will produce substantial slippage between rollers 21 and grinding face 18. This action will subject the material between the rollers and said face to a sliding grinding action in addition to the pressure crushing normally exerted in mills of this type. The brake will however have no appreciable effect until the bowl 16 is running at a substantial speed, thereby avoiding any increase in the starting torque of motor 11. 45

While the invention has been illustrated in its application to a roller mill of the type employing a plurality of rollers traveling along a horizontal ring, it will be apparent that the invention is not restricted to this construction and that various modifications may be made within the scope of the invention as set forth in the claims. Moreover while an annular screen registering with the margin of a bowl and arranged for relative rotation between the screen and the bowl has been illustrated, the invention as it relates to such screen is not restricted in its broadest aspects to this construction or arrangement. 70

I claim:

1. A roller mill comprising an annular grinding surface, freely rotatable grinding rollers traveling along the grinding surface in position for rotation by grinding engagement with material on said surface, shafts on which the rollers are fixed, generator type magnetic brakes associated with said shafts for retarding the rotation of the rollers and shafts, and means for heating material fed to the mill including an electrical heater energized by current from the generator type brakes.
2. A roller mill comprising a grinding bowl, a frame carrying rotatable grinding rollers within the bowl in position to be rotated by contact with material carried on the inner surface of the bowl, means for producing relative rotation between said frame and said bowl, shafts journaled in said frame carrying said rollers, a plurality of rotor drives one for each of said shafts, a plurality of driving members carried by said frame one for each rotor drive, and means for applying a variable torque between each driving member and its corresponding rotor so as to impose a variable torque on said shafts and rollers and independently vary the relative grinding speed of each roller with respect to the surface of the bowl and with respect to the speeds of the remaining rollers.
3. A roller mill as set forth in claim 2 in which each rotor drive and its cooperating driving member compose a motor generator unit adapted to apply torque in either direction on the corresponding roller shaft.
4. A roller mill comprising a grinding bowl, a frame carrying grinding rollers within the bowl, means for producing relative rotation between said frame and said bowl, said rollers being rotated on their axes by grinding engagement with material carried on the inner surface of the bowl and means for superimposing on each of said rollers separately a variable braking torque dependent upon the speed of rotation of each respective roller and producing an independently variable sliding movement of the operative grinding face of each roller relative to the grinding bowl.
5. A roller mill as set forth in claim 4 in which the grinding bowl is rotated and the roller carrying frame is substantially angularly immovable in operation.
6. A roller mill as set forth in claim 4 in which generator type magnetic brakes are associated with the roller shafts to apply the variable braking torque on each roller.

STANLEY D. HARTSHORN.
